(57) CLAIM

The ornamental design for pants, as shown and described.

DESCRIPTION

This application is an application for reissue of U.S. Design Pat. No. D654,661, which issued on Feb. 28, 2012 from U.S. Design patent application Ser. No. 29/396,448, filed Jun. 30, 2011, the entire contents of which are hereby incorporated by reference.

Notice: More than one reissue application has been filed for the reissue of U.S. Pat. No. D654,661. The reissue applications are application Ser. No. 29/483,494 (the present application), divisional reissue application Ser. No. 29/518,388, and divisional reissue application Ser. No. 29/559,022, all of which are reissues of U.S. Design Pat. No. D654,661.

FIG. 1 is a front view of pants according to a first embodiment of the design;

FIG. 2 is a rear view thereof;

FIG. 3 is a right side view thereof;

FIG. 4 is a left side view thereof;

FIG. 5 is a front perspective view thereof;

FIG. 6 is a rear view of pants according to a second embodiment of the design, the front, left side, and front perspective views being the same as FIGS. 1 and 4-5, respectively; [and.]

FIG. 7 is a right side view thereof[.];

FIG. 8 is a front view of pants according to a third embodiment of the design;

FIG. 9 is a rear view thereof;

FIG. 10 is a right side view thereof;

FIG. 11 is a left side view thereof; and,

FIG. 12 is a front perspective view thereof.

The symbol depicted in FIGS. 6-7 forming part of the claimed design is a registered trademark of Lululemon Athletica Canada Inc.

The portions of the pants depicted by broken line FIGS. 8 through 12 form not part of the third embodiment.

1 Claim, 12 Drawing Sheets

Matter enclosed in heavy brackets [ ] appears in the original patent but forms no part of this reissue; matter printed in italics indicates the additions made by reissue.
